United States Patent Office.

SAMUEL ROEBUCK AND JOHN ROEBUCK, OF BROOKLYN, NEW YORK.

Design No. 4,318, dated August 30, 1870.

DESIGN FOR A CUSPADORE.

The Schedule referred to in these Letters Patent and making part of the same.

To all whom it may concern:

Be it known that we, SAMUEL ROEBUCK and JOHN ROEBUCK, of the city of Brooklyn, county of Kings, State of New York, have originated and designed a new Pattern for "Cuspadores" or "Cospitores," of which the following is a full, true, and exact description, reference being had to the accompanying drawings forming part of this specification.

Figure 1 represents a perspective view of the cuspadore.

Figure 2, a sectional view through a line bisecting the cuspadore perpendicularly.

Similar letters of reference indicate similar parts.

A represents a hollow earthen vessel, capable of being used as a spittoon or receptacle for waste matter or the litter accumulating in parlors and other rooms, bar-rooms, &c., and known in the crockery and house-furnishing trades under the name of cuspadore or cospitore.

The peculiar configuration of A, as shown in the drawings, having a narrow neck, b, and a long, widely-flaring top, c, calculated to catch readily and lead

quickly into the body of the vessel d, any liquid matter deposited upon it, makes the cuspadore formed upon this design better adapted for its purpose as a spittoon than anything before produced, as we believe. At the same time it is well adapted for the reception of ornamentation on its outer surface, the style of which may vary, and forms no part of the design now claimed as new and of our invention.

Cuspadores have been articles of common use for a considerable number of years, but there has been little variation in the shapes, and we believe the shape of the cuspadore represented by A is desirable, useful, and new.

What we claim as our invention, and desire to secure by Letters Patent, is—

The design for cuspadores, substantially as herein set forth.

SAMUEL ROEBUCK.
JOHN ROEBUCK.
